UNITED STATES PATENT OFFICE.

ASAKICHI NAKAHARA, OF SEATTLE, WASHINGTON.

BRUSH.

Application filed March 19, 1923. Serial No. 625,972.

To all whom it may concern:

Be it known that I, ASAKICHI NAKAHARA, a subject of the Emperor of Japan, residing at Seattle, in the county of King and State 5 of Washington, have invented a new and useful Brush, of which the following is a specification.

My invention relates to improvements in brushes and more particularly to blacking 10 brushes, and the principal objects of my invention are to provide a brush whereby the polish is self contained within the back and with means for readily supplying the polish to the bristles of said brush at all times.

Another object is to provide the brush 15 with a cloth which may be drawn around under the bristles and covering same when in use for polishing and which may be folded over the back and out of the way when 20 not in use. Other objects are to provide a brush which is simple and durable in construction, positive and efficient in operation and which may be manufactured at comparatively small cost.

With the above and other objects in view 25 which will appear as the description proceeds, the invention consists of the novel construction, adaptation, arrangement and combination of parts hereinafter described 30 and claimed.

These objects are accomplished by devices illustrated in the accompanying drawings, wherein—

Figure 1 is a view in front side elevation 35 of the device;

Figure 2 is a top plan view of same;

Fig. 3 is a view in longitudinal vertical section taken substantially on a broken line 3, 3 of Fig. 2;

Fig. 4 is a view in longitudinal horizontal section taken substantially on a broken line 4, 4 of Fig. 1;

Fig. 5 is a view in transverse vertical section taken on a broken line 5, 5 of Fig. 2;

Fig. 6 is a view in transverse vertical section taken on a broken line 6, 6 of Fig. 1; and

Fig. 7 is a view in rear side elevation of the device.

Referring to the drawings throughout which like reference numerals designate like parts, the numeral 5 designates the back, the numeral 6 designates the polishing bristles, and the numeral 7 designates the dauber 55 bristles.

The back 5 is cut to form an L-shaped

base member 8 and a complementary cover member 9 pivotally secured to said base member by hinges 10 and 11 and which may be locked thereto in the closed position by 60 hooks 12 and 13. By virtue of the L-shaped base member 8, a head 14 is formed thereon to which the dauber bristles 7 are secured in the usual manner.

A transverse slot 15 is provided in the 65 outer end of the head 14 and extends from the bristles 7 to a hole 16 extending transversely through said head. A stopcock 17 fits within said hole and is provided on its exterior end with a head 18 by means of 70 which same is manually operated. Said stopcock is provided with a triangular shaped slot 19 adapted to register with the slot 15, and a circular aperture 20 extends from said triangular slot through said stopcock and registers with a corresponding aperture 21 extending through the head 14 and communicating with a longitudinal chamber 22.

The chamber 22 extends from the head 80 14 nearly the full length of the back 5 and is substantially circular in cross section, one half of same occupying the base member 8 and the other half the back member 9. Said chamber is positioned to one side of 85 said back and a longitudinal slot 23 provided in the sides of said members extends the full length of said chamber. A recess 24 is provided in said members at the rear end of said chamber and the inner end of the 90 aperture 21 is threaded for reasons presently described.

In the operation of the device a collapsible tube 25 containing polish paste is placed within the chamber 22 by screwing its 95 threaded neck 26 into the aperture 21 and by pressing its closed end into the recess 24 to prevent same from slipping. A ball 27 is then pressed into place at the closed end of said tube and the back members 8 and 100 9 are locked together by means of the hooks 12 and 13.

It will be understood that the stopcock 17 is ordinarily closed as indicated in dotted lines in Fig. 3 of the drawings. When it is 105 desired to apply the polish said stopcock is turned to the open position shown in full lines and the ball 27 is pressed forward by the thumb through the slot 23. The paste will be forced outwardly through said stopcock and transverse slot 15 and the bristles 7 110 will be saturated thereby.

The polish is then applied to the shoe in the ordinary manner and is thoroughly brushed in by the bristles 6. The cloth 28 is then drawn from the position shown in Fig. 3 around under the bristles 6 where it is secured as shown in Fig. 1, and by means of said cloth a finished polish is given to the shoe.

It will thus be seen that every element necessary in polishing the shoe is self contained within the device and that the entire operation may be performed without the loss of time and inconvenience in shifting from one device to another.

From the foregoing description taken in connection with the accompanying drawings the form of construction and method of operation of my brush will be readily apparent to those skilled in the art to which the invention relates, and it will be understood that the apparatus shown is merely illustrative and that such changes may be resorted to as are within the scope and spirit of the invention.

Having thus described my invention, what

I claim and desire to secure by Letters Patent is:—

A brush of the character described comprising a base and a cover member, hinges connecting said members, locking means for said members, a head on said base member, dauber bristles on said head, said base and cover members having a longitudinal chamber disposed therebetween, said head having a passageway communicating between said chamber and said dauber bristles, a collapsible tube within said chamber having its neck threadedly secured within said passageway and its tail secured within a recess, said base and cover members having a longitudinal complementary slot in inter-communication with said longitudinal chamber, a ball within said chamber adapted to be manually pressed against said collapsible tube through said longitudinal slot to force its contents through said passageway to said dauber bristles, and a stopcock for controlling the passage of said contents from said tube.

ASAKICHI NAKAHARA.
